UNITED STATES PATENT OFFICE.

DELLA GRAEME SMALLWOOD, OF WASHINGTON, DISTRICT OF COLUMBIA.

DESIGN FOR A SPOON.

SPECIFICATION forming part of Design No. 22,559, dated June 27, 1893.

Application filed May 13, 1893. Serial No. 474,146. Term of patent 7 years.

To all whom it may concern:

Be it known that I, DELLA GRAEME SMALLWOOD, a citizen of the United States, residing at Washington, in the District of Columbia, 5 have invented a new and original Design for Spoon-Handles; and I do declare the following to be a full, clear, and exact description of the invention, such as will enable others skilled in the art to which it appertains to 10 make and use the same, reference being had to the accompanying drawing, and to the letters of reference marked thereon, which form a part of this specification.

The object of the design is to produce a 15 souvenir for schools, and the main feature is a spoon having delineated upon its handle, emblems characteristic of the different branches of study taught in educational institutions.

The accompanying drawing represents the 20 spoon formed with spaces suitable for illustrating at *a* an emblem indicative of geom-

etry, and at *b* an emblem indicative of algebra. At *c* is shown an open book indicative of history, at *d* an emblem indicative of music, at *e* a palette and brushes indicative of art, and at *f* Indian club and dumb-bells indicative of 25 physical culture.

At *g* *h* are scrolls upon which may be inserted any suitable emblem of study.

At *i* is a space for any suitable inscription. 30 At *p* is a representation of the pen, an article common to all institutions of learning.

I claim—

The design for spoons substantially as 35 shown and described.

In testimony whereof I affix my signature in the presence of two witnesses.

DELLA GRAEME SMALLWOOD.
